GAS STOVE

John C. Rogers, Cicero, Ill., assignor to Crown
Stove Works, Cicero, Ill., a corporation of Illinois

Application August 14, 1933, Serial No. 684,997

1 Claim. (Cl. 126—39)

This invention relates to the general art of gas stoves or ranges and has reference more particularly to an improved burner top for the same.

More particularly, the present invention relates to a known type of gas stove or range wherein the burner top plate is provided with depending flame guards below the burner openings therein which, at their lower ends, encircle the burners and are designed to conserve heat by preventing the flames from spreading laterally through the space between the burner top plate and the usual drip pan and directing substantially the entire body of the flame against the bottom of the cooking vessel, thus increasing the portion of the total heat usefully employed in the cooking operation.

Among the objects of the invention are, to reduce the cost of manufacture of burner top plates of this type, simplify the construction and reduce the number of parts heretofore used, provide easy access to the burners, drip pan and other underlying parts, and provide a modification of the modern type of gas stove or range that will spell both greater economy of fuel and increased cooking efficiency.

One practical form in which the invention may be embodied is illustrated in the accompanying drawings, in which—

Fig. 1 is a top plan view of a burner top, its supporting frame, and a group of four burners, the burner top being provided with the improved flame guards of the present invention.

Fig. 2 is a front rear section taken on the line 2—2 of Fig. 1.

Fig. 3 is a transverse section on the line 3—3 of Fig. 1.

In the construction shown, the invention is applied to a gas stove comprising vertical side and rear walls 10 and 11 respectively, a top frame 12 formed with an internal ledge 13 supporting a pair of removable burner top plates 14 equipped with grate bars 15, burners 16 carried by mixing tubes 17 supplied with fuel from a front manifold 18, and removable burner grates 19 supported in seats 20 formed in the burner plates 14, these seats surrounding openings 21 in the burner top plates 14 directly above the burners.

Continuous with the seats 20 which form the margins of the openings 21, are depending flame guards. In the preferred form of such guard, the same comprises an upwardly flaring upper portion 22 and a substantially cylindrical lower portion 23 which, as clearly shown in Figs. 2 and 3, completely surrounds the upper portion of the burner, with a slight clearance sufficient to admit the flow of secondary air to the flame. These flame guards may be integral with the burner top plate, as shown, or attached thereto, but however they may be connected to the top plate, they are continuous with the latter so as to form a complete barrier against the lateral spread of flame through the space underlying the burner top plates. In this way, practically the entire amount of heat given off by the flame is applied directly to the bottom of the cooking vessel on the grate 19.

To insure an adequate volume of secondary air, the burner tops 14 are formed with marginal holes 24 (Fig. 1) that admit air freely to the space below the plates, which air is then drawn upwardly by the heat of the burner flames through the space between the lower end of the flame guard and the burner itself.

I claim:

In a multiple burner gas stove, the combination with a top frame formed with an internal countersunk marginal ledge, and burners located below said frame, of a plurality of removable burner top plates seated on said ledge in edge-to-edge contact and equipped with aligned grate bars, each of said burner top plates and its grate bars having openings therethrough directly over a corresponding number of burners and of greater diameter than said burners, integral imperforate upwardly flaring flame guards continuous with and depending from the margins of said openings respectively and formed with cylindrical lower open end portions encircling said burners with unobstructed clearance for the flow of secondary air, and removable burner grates seated in the upper ends of said flame guards.

JOHN C. ROGERS.
